UNITED STATES PATENT OFFICE

163,896

GRAVE MARKER

Glen R. Nichols, Chicago, Ill.

Application September 2, 1950, Serial No. 12,040

Term of patent 3½ years

(Cl. D79—2)

To all whom it may concern:

Be it known that I, Glen R. Nichols, a citizen of the United States, residing at Chicago, in the county of Cook, and State of Illinois, have invented a new, original, and ornamental Design for a Grave Marker, of which the following is a specification, reference being had to the accompanying drawing, forming part thereof and wherein:

Fig. 1 is a face view of a grave marker, showing my new design, and,

Fig. 2 is an edge view of the grave marker. The dominant characteristics of the design are shown in full lines in the drawing.

I claim:

The ornamental design for a grave marker, as shown and described.

GLEN R. NICHOLS.
